PROTECTIVE DEVICE

Emil Kolisch, New York, N. Y., assignor, by direct and mesne assignments, to Continental Silver Co., Inc., Brooklyn, N. Y., a corporation of New York

Application August 9, 1947, Serial No. 767,696

14 Claims. (Cl. 219—44)

1

This invention relates to protective devices, more especially for electrical appliances of the type used in the home or in the offices of physicians and dentists and particularly to a device which breaks the circuit when the appliance is overheated and may be readily reset to operativeness and, though applicable to heaters for water, liquids or fluids generally, such as for sterilization or for culinary purposes, is shown herein applied to a coffee percolator.

It is among the objects of the invention to provide a protective device for an electrical heating appliance of the above type which is of simple, relatively inexpensive, compact and rugged construction, which does not detract from the normal operation of the appliance, which is not exposed to contact with the materials to be heated by the appliance and which yet may be completely concealed from the exterior of the appliance, which will function to interrupt the circuit upon overheating of the appliance as for instance, in the absence of desired liquid therein, which functions without appreciable arcing both in maintaining the circuit in use and in interrupting the circuit upon overheating, and which admits of being instantly and unerringly restored to operativeness by the unskilled user by resort to a simple manipulation, such as the turn of a knob accessible from the exterior of the appliance and without the need for any tools for disassembly, or for reaching into the interior of the device.

It is a feature of the invention to provide a plurality of fusible links of which one only is maintained in operative position where it is subjected to the heat evolved in the appliance, the remaining fusible links being in reserve for ready replacement upon fusing of the link in use under excessive heat. To this end the fuse link in action is in engagement with a stop or contact in effective heat conducting relationship with the heating element of the appliance. The stop and the fusible link are relatively displaceable, preferably by a manual member accessible from the exterior, such as for instance from the bottom of the appliance for readily replacing a fused link with a reserve link. Preferably each link is mounted on the free end of a spring arm and the stop member has associated therewith, desirably as an integral part thereof, a camming

2

guide to deflect the link into engagement with the stop and at the same time to stress the spring arm so that upon softening of the fusible link in action under excessive heat, the same will readily be ruptured under the stress of the spring arm to sever the link and cause disengagement from the stop. In a preferred construction the fusible links radiate from a rotatable mount which desirably rises from the bottom of the device and to which is affixed the manually operated knob, while the stop is affixed thereabove with its associated cam guide. While the electrical circuit may extend through the fusible link, it is within the scope of the invention from its broader aspects to have the electrical circuit by-pass the fusible link but to be automatically opened by the spring release action upon severing of the fusible link.

Another feature of the invention is the provision of means on the rotatable mount to enable it to rotate only in one direction, thereby ensuring that the link will properly engage the cam guide so that it may be deflected into engagement with the contact.

25 In the accompanying drawings in which are shown one or more of various possible embodiments of the several features of the invention,

Fig. 1 is a fragmentary perspective view of the electrical appliance,

30 Fig. 2 is a cross sectional view taken along line 2—2 of Fig. 1,

Fig. 3 is a cross sectional view taken along line 3—3 of Fig. 2,

35 Fig. 4 is a view partly in cross section taken along line 4—4 of Fig. 2,

Fig. 5 is a perspective view of the cam guide and contact,

40 Fig. 6 is a dropped perspective view on a smaller scale showing the heating element and mount therefor, and

Fig. 7 is a fragmentary perspective view on a smaller scale of another embodiment of the invention.

45 Referring now to the drawings there is shown a preferred embodiment of the protective device as applied to a coffee percolator 10. The latter comprises a container 11 affixed to a hollow base 12 which has a bottom plate 13 affixed thereto by means of screws 14 which pass through the bottom rim 15 of the base and are threaded into

corresponding openings 16 in the upturned peripheral rim 17 of the bottom plate 13.

Carried by the top 18 and extending through an opening 19 therein is a generally cylindrical, preferably ceramic mount 22. A cylindrical protective housing 20 encompasses that portion of the mount which protrudes above top 18 and has an inturned rim 21 extending under diametrically opposed laterally extending ears 23 integral with the mount 22. To permit assembly of the housing 20 to the mount, the rim 21 may have diametrically opposed slots 21' to accommodate said ears 23 so that upon slight rotation of the housing 20, after introduction of the ears into the slots 21', the housing is attached relative to the mount. A nut 24 secured upon the threaded lower end 25 of the mount 22 causes the ears 23 to be pressed against the inturned rim 21 of the housing, rigidly to clamp the housing and the mount to the base.

A high resistance wire 28 is wound around the upper end 26 of the mount 22 which is of slightly reduced diameter forming an annular ledge 27. One end 29 of the wire is connected to the head of a bolt 30 which extends through a bore 31 in the ledge 27 and the mount 22, and protrudes from the bottom of the mount as at 32, being retained therein by a nut 33. The other end 34 of the resistance wire 28 passes through a bore 35 in the ledge 27 and mount 22 and extends from the bottom of the mount as at 36 and is connected by a lead 37 to a terminal plug 38 rigidly affixed to an insulating plate 39 mounted on the wall of the base 12 as is the companion terminal plug 40.

The protective device disposed within the hollow base 12 establishes an electric circuit from the two ends 29 and 34 of the heating coil to the two terminals 38 and 40 respectively. This device includes a plurality of fusible links 61 each carried by a corresponding contact arm 59. An electrical contact closes circuit to one only of said arms. The rupture of the fusible link under excessive heat results in automatic interruption of the electric circuit, preferably under release of stress resiliently imposed in operative position. The contact and the fusible links are then relatively displaceable by manual action to restore the circuit. It is, of course, not necessary that the entire length of the link be of fusible material but only a portion thereof need be in order to break the circuit when such fusible portion ruptures.

The embodiment of the protective device herein chosen to illustrate my invention comprises a cam guide 41 of heat conducting metal such as sheet metal having a curved cam arm 42 with a bend 43 therein and preferably having a substantially U-shaped contact or stop portion 44 at one end thereof which is preferably substantially square in cross section. An arm 45 unitary with the cam guide 41 extends at substantially right angles thereto and is affixed to the bottom end of bolt 30 by a nut 46, as shown in Figs. 2, 4 and 5.

Mounted on bottom plate 13 within the base is a rotatable mount comprising a circular block 47 of insulating material and a substantially cup shaped carrier 48 of metal. The cup shaped carrier 48 is affixed to the upper surface of the block, preferably by means of rivets 49 which are headed as at 50 and which extend through the bottom of the cup into countersunk opening 51 in the block 47.

In order to provide a convenient means for rotating the mount from the exterior of the base,

10 a screw 52 is provided which passes through and is rigidly affixed to the cup shaped carrier 48 and block 47 at the axis thereof. The end 53 of the screw extends through an opening 50' at the center of the bottom plate 13, the latter being spaced from the table on which the appliance is placed by means of a plurality of legs 54 to afford clearance for a knob 55 which is affixed by means of a set screw 56 therethrough to the end 53 of the screw 52.

15 Rigid with the upturned rim 57 of the cup or carrier 48 are upstanding spring arms 59 which are of spring metal. In the embodiment herein, four such arms are shown, although more or less could be used. The arms 59 are preferably affixed to rim 57 as by rivets 58 although they might be integral therewith. The upper end of each of the spring arms has a pair of laterally extending ears 60 which clamp the upwardly extending link 61 therebetween. The length of the spring arm 59 and its associated contact or link 61 is such that the link 61 will reach above the bottom edge 64 of the cam guide 41, and when the mount is rotated by knob 55 the link 61 that faces the stop 44 will be cammed inwardly by cam guide 41 to tense the associated spring arm 59 and force link 61 into said stop. The link is of fusible metal and preferably is square in cross section, as shown in Fig. 4, to correspond to the substantially U-shaped contact or stop portion 44 at the end of the cam guide 41. As shown in Fig. 2, stop 44 is inclined slightly so that when link 61 is cammed therein by cam guide 41, the entire inner face of the stop 44 will be in contact with link 61 at the end of the now inclined and flexed arm 59 thereof.

20 A resilient contact arm 65 is affixed at one end to terminal post 40 as at 66 and is in electrical contact at its free end 67 with the metal cup 48. In order to limit the rotation of the mount to one direction only, block 47 is preferably provided with a plurality of ratchet teeth 69 on the periphery thereof which coat with ratchet pawl 70 pivoted at 71 to the bottom plate 13 and resiliently urged against the periphery of the block 47 by spring 72. In the embodiment herein, four ratchet teeth are shown on the block corresponding at least to the number of spring arms 59 and equally spaced therefrom but a greater number could be used if desired.

25 With a link 61 in stop 44, as shown in Figs. 2 and 4, the container 10 is filled with liquid and a source of current is applied to terminal plugs 38 and 40. The circuit is from terminal plug 38, lead 37, heating element 28, bolt 30, cam guide 41, contact 44, link 61, spring arm 59, metal cup 48, contact arm 65 to the other terminal. Since a good heat conducting path is established from the source of heat to the metal stop 44, over-heating (as for instance in the absence of liquid) will cause the engaged link 61 to soften. Before the fusible link melts, its mechanical strength will have been so greatly reduced that it will be sheared under the tension of the spring arm 59 which will snap outwardly, thereby breaking the circuit so rapidly that there is no danger of arcing.

30 But for this mechanical shearing action, if the user should cut off the electric current when the fusible link had just begun to soften and had been deformed from its original shape, it would remain in this deformed condition when the apparatus was permitted to cool to normal temperature. The deformity of the link might cause only slight contact to be made between the link

and the contact 44, resulting in a high resistance joint which upon passage of current therethrough upon further use of the appliance might cause sufficient heat to develop at the point of contact to melt the link even though the container was full of water and the appliance operating normally.

As the links other than the one in operation, are not in contact with any heat conducting metal such as the stop 44, although the temperature in the base will rise due to overheating in container 11, this rise will not be sufficient to weaken them before the circuit is broken by the rupture of the link in operative position.

The user, noticing that the device is not operating, will turn knob 55 to again complete the heating circuit. As the link that formerly had been in contact 41 has been sheared, there is nothing to impede the clockwise rotation of the knob 55, as shown in Figs. 1 and 2.

When the knob is turned in a clockwise direction, link 61 will first abut against the leading edge of the cam arm 42 and be thereby forced inwardly against the tension of spring arm 59. As the knob is rotated further, the link will ride over the bend 43 in the cam arm and then snap into contact 44. It is to be noted that even when link 61 is seated in contact 44, the spring arm 59 will still be tensed, thereby retaining the link in the contact. The configuration of the contact and the link will thereupon prevent any further rotation of the knob and a positive contact will be made that will not jar loose.

In the embodiment shown in Fig. 7, similar parts have their reference numerals primed. In this embodiment an insulated post 75 is provided rigid with the carrier 48' and extending upright therefrom at the axis thereof. Affixed to the upper end of the insulated post 75, as by a screw 76, is a spider 77 having a plurality of radiating arms 78 of conducting material, each of which is aligned with one of the spring arms 59' and so spaced therefrom that when the spring arms 59' are in upright position they will not engage the arms 78 and when a spring arm 59' has been carried inwardly and tensed by cam guide 41', it will contact the end of an arm 78 as at 79. End 29' of resistance wire 28' extends through a bore 80 in ledge 27' and insulating mount 22', and is connected by a lead 82 to spider 77.

The embodiment shown in Fig. 7 operates in a manner similar to that of Figs. 1 to 6 except for the fact that the fusible link serves as a retaining device for holding a spring arm 59' and conducting arm 78 in contact, but no current passes therethrough. Under excessive heat, link 61' will soften and the tension of spring arm 59' will cause the latter to snap outwardly, sheathing the now soft link 61' and thereby breaking the contact between arm 78 and spring arm 59'. When cup 48' is rotated, and link 61' with its associated spring arm 59' is urged inwardly by cam guide 41', the spring arm will engage its associated contacting arm 78 to make contact therewith, thereby completing the circuit to the source of current as from lead 37', resistance cone 28', lead 82 to spider 77, arm 78, spring arm 59', cup 48' and spring contact arm 65'.

Thus by the device hereinabove described, an efficient protective device is provided that will positively break the circuit in the event of any overheating, yet can quickly and simply be adjusted to restore the appliance to operative condition without the need for special skill or any tools.

When all the fusible links have been melted, it is a relatively simple matter to remove the bottom plate 13 by unloosing screws 14. The entire carrier unit can then be replaced by a new unit or the arms 60 at the ends of the spring arm 59 may be spread apart, the stubs of the old links removed and new links installed with only the use of a pair of pliers.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention what I claim as new and desire to secure by Letters Patent of the United States is:

- 20 1. A protective device for electric heating appliances, said device comprising a mount having a plurality of spring arms thereon, a fusible link at the end of each of said spring arms, a contact of heat conducting material, a cam associated with said contact, means to effect relative movement of the contact and the fusible links for abutment of one of said links against said cam to guide said link along said cam into engagement with said contact to maintain the associated arm in circuit and to tense said arm, whereupon the arm will be snapped out of circuit by weakening of the engaged link.
- 25 2. A protective device for electric heating appliances, said device comprising a rotatable mount, a plurality of spring arms rotatable with said mount, a fusible link at the end of each of said spring arms, a fixed contact of heat conducting material normally out of the path of rotation of said fusible links, and means associated with said fixed contact and in the path of rotation of said fusible links after rupture of the engaged link to bring the next fusible link into engagement with said fixed contact to maintain the corresponding spring arm in circuit and to tense said spring arm, whereupon the arm will be snapped out of circuit by weakening of the engaged link.
- 30 3. A protective device for electric heating appliances, said device comprising a rotatable block, a plurality of spring arms rotatable with said block, a fusible link at the end of each of said spring arms, a fixed contact of heat conducting material normally out of the path of rotation of said fusible links, and a cam guide associated with said fixed contact and in the path of rotation of said fusible links successively to bring said links into engagement with said fixed contact to maintain the corresponding spring arm in circuit.
- 35 4. The combination set forth in claim 3 in which means are provided coacting with said block to limit the direction of rotation thereof.
- 40 5. A resettable protective device for electric heating appliances, said device comprising a rotatable insulating block, a carrier affixed to said block, a plurality of spring arms rigid with said carrier and rotatable therewith, a fusible link at the end of each of said spring arms, a fixed contact of heat conducting material normally out of the path of rotation of said fusible links, and a cam guide associated with said affixed contact and in the path of rotation of said fusible links successively to bring said links into engagement with said fixed contact to maintain the corresponding spring-arm in circuit and to
- 45
- 50
- 55
- 60
- 65
- 70
- 75

stress said spring arm, whereupon the arm will be snapped out of circuit by weakening of the engaged link.

6. A resettable protective device for electric heating appliances, said device comprising a rotatable insulating block, a carrier affixed to said block, a plurality of spring arms rigid with said carrier and rotatable therewith, a fusible link at the end of each of said spring arms, a fixed contact of heat conducting material engaged by one of said links and maintaining the corresponding arm in circuit and normally out of the path of rotation of said fusible links, a cam arm unitary with said fixed contact and in the path of rotation of said fusible links, successively to deflect each of said spring arms inwardly to stress the latter and to bring its associated link into engagement with said fixed contact, the tension of said spring arm thereby aiding in retaining said link in said contact.

7. A resettable protective device for an electrical unit of the type having a heating element, said device comprising a rotatable insulating block, a metal cup shaped carrier affixed to said block, a plurality of spring arms affixed at one end to the rim of said cup, a fusible link at the free end of each of said spring arms, a cam guide of heat conducting metal in electrical circuit with such heating element and in the path of rotation of said fusible links, a substantially U-shaped contact unitary with said cam guide at one end thereof and normally out of the path of rotation of said fusible links, and means to rotate said block and said carrier, thereby successively to bring each of said links into contact with said cam guide to deflect each of said spring arms inwardly and to cam said link into engagement with said contact.

8. The combination set forth in claim 7 in which means are provided, resiliently urged against the rim of said metal cup shaped carrier to make contact therewith.

9. The combination set forth in claim 7 in which said fusible link and said U-shaped contact are substantially square in cross section, thereby to retain said link in said contact under the tension of said deflected spring arm.

10. A resettable protective device for an electrical unit of the type having a heating element, said device comprising a rotatable insulating block, a metal cup shaped carrier affixed to said block, a plurality of spring arms affixed at one end to the rim of said cup and rotatable therewith, a fusible link at the free end of each of said spring arms, a cam guide of heat conducting metal in electrical circuit with such heating element and in the path of rotation of such fusible links, a substantially U-shaped contact unitary with said cam guide at one end thereof and normally out of the path of rotation of said fusible links, and means resiliently urged against the rim of said cup shaped carrier to make contact therewith, means to rotate said block and said carrier, thereby successively to deflect each of said spring arms inwardly and to cam the link thereof into engagement with said contact, and ratchet means coacting with said block and said carrier to limit the direction of rotation thereof.

11. A resettable protective device for an electrical appliance of the type having a base, a bottom plate, a heating element affixed to the top of said base and terminal plugs for connecting a source of current to such heating element, said device comprising an insulating block rotatably mounted on such bottom plate, a cup shaped car-

rier affixed to said block and rotatable therewith, a plurality of spring arms rigid with said carrier at the rim thereof and rising therefrom, a fusible link at the end of each of said spring arms, a cam guide including a contact, electrically connected to one end of such heating element and depending from the top of such base in the path of rotation of said fusible links, and a contact arm affixed at one end to one of such plugs and having its free end resiliently urged against the rim of said cup shaped carrier to make contact therewith.

12. A resettable protective device for an electrical appliance of the type comprising a base, a bottom plate affixed thereto, a heating element affixed to the top of said base and terminal plugs for connecting a source of current to such heating element, said device comprising an insulating block, a metal cup shaped carrier affixed to said block, means rigid with said block and passing through such bottom plate for manually rotating said block and said carrier, means on such bottom plate coacting with said block to limit the rotation thereof, a plurality of spring arms rigid with said carrier and rising upwardly therefrom, a fusible link affixed to the free end of each of said spring arms, a contact connected to one end of such heating element and depending from the top of such base, means associated with said contact and in the path of rotation of said fusible links successively to cam said spring arms inwardly, thereby tensing the same as said block is rotated and successively moving said links into engagement with said contact, the tensed spring arm thereupon aiding in retaining said link in engagement with said contact, and a contact arm affixed at one end to one of such terminal plugs and having its free end urged against the rim of said cup shaped carrier.

13. The combination set forth in claim 12 in which the means on such bottom plate coacting with said block to limit the rotation thereof comprises a plurality of ratchet teeth on said block at the periphery thereof and a ratchet pawl pivotally mounted on such bottom plate and resiliently urged against the periphery of said block.

14. A resettable protective device for an electrical appliance of the type comprising a base, a bottom plate affixed thereto, a heating element and terminal plugs for connecting a source of current to such heating element, a substantially cylindrical insulating mount affixed to the top of such base, extending through an opening therein, and supporting such heating element, a substantially cylindrical casing affixed to such base and encompassing such heating element, and a bolt extending through an opening in such mount, connected at its upper end to one end of such heating element and protruding from such mount at its lower end, said device comprising a cam guide affixed to the protruding end of such bolt, an insulating block, a metal cup shaped carrier affixed to said block, means rigid with said block and passing through such bottom plate for manually rotating said block and said carrier, a plurality of spring arms rigid with said carrier and rising upwardly therefrom, a fusible link affixed to the end of each of said spring arms, the path of rotation of said spring arms and said links causing said links successively to abut against said cam guide, thereby urging said spring arms inwardly, a stop on said cam guide to retain said link in contact therewith and a contact arm affixed at one end to one of such

terminal plugs and having its free end urged against the rim of said cup shaped carrier.
